EARTH BORING BIT

John Allen Moore, Denver, Colo.

Application November 15, 1951, Serial No. 256,545

2 Claims. (Cl. 255—61)

1

This invention relates to an earth boring bit, and is more particularly designed to be placed on the extremity of a length of pipe for boring a horizontal hole for the pipe from a water main in a street to a residence or other service connection.

The principal object of the invention is to provide a boring bit of this type which will be simple and economical to manufacture; which will be highly efficient and self-cleaning in use; and which will eliminate clogging of the water passages from foreign materials in the water supply.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved earth boring bit;

Fig. 2 is a front end view thereof;

Fig. 3 is a longitudinal section through the bit, taken on the line 3—3, Fig. 2; and

Fig. 4 is a side view of the bit during a preliminary step in its manufacture.

The improved bit is preferably manufactured from a short length of heavy wall steel tubing 10 having external pipe coupling threads 11 formed on its one extremity. A plurality, preferably four, of uniformly spaced slots 12 are cut into the other extremity of the length of tubing 10 to form uniformly separated, toothed fangs 13. The leading edge of each fang is notched inwardly, as shown at 14, to form a relatively sharp, hook-like extremity on the fang. The trailing edge of each fang is arcuately curved, as shown at 15, to accentuate the sharpened extremity of the fang and to provide clearance therefor.

The formed fangs are then separated and spread outwardly and forwardly, as shown in Fig. 1, to form a flower-like, flaring extremity, with the point of each fang uniformly separated from the points of the adjacent fangs, and with the points spaced outwardly from the surface of the tubing 10 a distance in excess of the exterior radius of the tubing. The fangs may, if desired, be heat-treated to increase their wearing qualities.

2

A tubular plug member 16 is mounted within the tubular portion of the tubing 10 in any desired manner, such as by means of screw threads, welding, soldering, shrinking, etc. As illustrated in Fig. 3 of the drawing, the plug member 16 is threaded into the tubular portion of the tubing 10.

A water jet tube 17 is fixedly and coaxially mounted in the plug member 16 and extends 10 completely through the latter, projecting rearwardly from the tubing 10. The rear extremity of the jet tube is reduced in diameter to provide a restricted water intake opening 18. The jet tube is also diametrically drilled to 15 form side water ports 19 in that portion of the tube which projects from the plug member 16. The diameter of the ports is less than the internal diameter of the jet tube 17.

In use, the threads 11 are screwed into a pipe 20 coupling, and the pipe coupling is threaded onto one extremity of a length of water pipe. The other extremity of the length of pipe is provided with any of the usual rotating braces whereby the pipe may be rotated and forced forwardly 25 while water under pressure is supplied therethrough.

The pipe is rotated in a clockwise direction to cause the sharp, hooked, toothed fangs 13 to cut a circular bore through the earth as the pipe is forced therethrough. The earth cuttings are washed rearwardly between the widely spaced, toothed fangs and discharge from the entrance of the bore. In addition to washing the earth rearwardly, the velocity of the water jet exiting 35 from the jet tube is sufficient to cut and wash away hard, packed earth ahead of the jet.

Sand and earth occasionally get into the bore pipe during the attachment of the hose thereto. These foreign materials, however, cannot clog 40 the jet tube, since the restricted intake opening 18 and the restricted ports 19 prevent particles of sufficient diameter to clog the jet tube 17 from reaching the latter.

While a specific form of the improvement has 45 been described and illustrated herein, it is to be understood that the same may be varied, within the scope of the the appended claims, without departing from the spirit of the invention.

Having thus described the invention, what is 50 claimed and desired secured by Letters Patent is:

1. An earth boring bit comprising a relatively short length of steel tubing; a plurality of relatively sharp fangs formed on one extremity of 55 said tubing, said fangs extending outwardly and

forwardly from said tubing to form a flower-like, flaring extremity thereon; a plug member fixedly mounted within and extending substantially throughout the length of said tubing and closing the latter; a water jet tube coaxially mounted in said plug member, said jet tube being fixedly supported by said plug member so as to project rigidly rearward of the latter; a reduced-diameter rear extremity on said jet tube; and means for coupling said tubing to a drilling member.

2. An earth boring bit as described in claim 1 having side water ports formed in the rearwardly projecting portion of said jet tube.

JOHN ALLEN MOORE.
